BENDING ROLLS MACHINE

Paul Parcells, Chicago, Ill., assignor to Geo. Whiting Company, a corporation of Illinois

Application May 10, 1935, Serial No. 20,870

5 Claims. (Cl. 153—61)

This invention relates particularly to bending rolls machines, such machines being commonly employed for forming sheet metal pipes, which may be either corrugated or non-corrugated.

5 Sheet metal corrugated pipes are commonly employed for culvert purposes.

Machines for forming large sheet metal pipes are ordinarily of heavy construction. To enable the pipe to be removed from the roll about which the sheet metal is bent into tubular form, the bearing at one end of the roll is made withdrawable to enable the formed pipe to be slipped off the roll. It is known practice, also, to provide means for shifting from its normal position the roll about which the pipe is formed, after the bearing at one end of the roll has been withdrawn.

The primary object of the present invention is to facilitate the withdrawal and the return 20 to normal position of the removable bearing of the roll, thus facilitating the work, in the case of heavy machines, of removing the pipe from the machine after it has been formed.

The invention is illustrated in a preferred embodiment in the accompanying drawings, in which—

Fig. 1 is a vertical longitudinal sectional view of a machine embodying the invention, taken as indicated at line 1 of Fig. 2; Fig. 2, an end 30 elevational view of the same; Fig. 3, a transverse vertical sectional view taken as indicated at line 3 of Fig. 1; and Fig. 4, an inner side elevational view of the counterweighted swinging standard which is provided with a bearing for the 35 free end of the roll upon which the metal pipe is to be formed.

In the embodiment illustrated, A designates a frame, shown as comprising longitudinal base-members A', main end-standards A² and A³, and 40 an intermediate standard A⁴, these standards being carried by the longitudinal base-members A'; A⁵, a swinging-standard mounted on a transverse pivot 1 carried by the main end-standard A³, the standard A⁵ being provided in its upper 45 end with a bearing 2; B, a set of bending-rolls suitably supported in the frame, shown as comprising a lower roll B', a back-roll B², and a shiftable upper roll B³, the latter being the roll about which the pipe is to be formed.

50 The roll B' is shown journaled in bearings 3 and 4 which are vertically adjustable in the standards A³ and A⁴, respectively. The roll B² is mounted in adjustable bearings 5 with which the standards A³ and A⁴ are provided. The roll 55 B³ has its front end-portion (drive end of ma-

chine) journaled in bearings 6 and 7 forming a part of a yoke 8, the bearings being in the form of eccentrics journaled in portions 9 of the standards A² and A⁴.

The yoke 8 may be moved through the medium of a hand-lever 10 in a known manner to shift the roll B³ to a somewhat diagonal position after the standard A⁵ has been swung to the full-line position shown in Fig. 1. Shifting the rear end of the roll B³ laterally is a known expedient for getting the roll sufficiently removed from normal position to enable the formed pipe to be removed from the roll.

The bearings 3 and 4 are vertically adjustable in a known manner through the medium of a longitudinally disposed shaft 11 which is equipped with a hand-wheel 11^a, said shaft being journaled in brackets 12 carried by the standards A³ and A⁴. The bearings are carried by vertical screws 13 which are actuated by nuts formed in bevel-pinions 14 which are actuated by bevel-pinions 15 secured on the shaft 11. The shaft 11 is disposed medially at the lower portions of the standards A³ and A⁴; and the bevel-pinions are housed below the medial portions of the standards mentioned.

Adjustment of the bearings 5 is accomplished through mechanism 16, in known manner.

A shaft 17, equipped with a large gear 18, serves to actuate the rolls through the medium 30 of pinions 19 which gear the rolls positively together. The large gear 18 may be actuated by a pinion driven by a suitable motor, or in any desired manner.

The swinging standard A⁵ which is located 35 outside the main end-standard A³ is normally secured in vertical position in any desired manner. As shown in Fig. 2, the casting of the end-standard A³ is provided with heavy lugs 20 whose lower ends support the pivot 1; and the standard A⁵, in the normal position, is housed between the vertical surfaces 21 afforded by said lugs. A locking-disk 22 is shown supported on a pivot 23. This locking-disk drops by gravity to the locking position shown in Fig. 2. It may 45 be swung away from this position through the medium of a stud 24 to unlock the swinging standard A⁵.

Depending from the standard A⁵ is an angular-form counterweight C, which is shown as comprising a bent arm 25, having one end secured, as by bolts 25^a, to the standard A⁵, and having the other end equipped with a weight 26 secured to the lower end of the arm, as by bolts 27. The elbow 28 of the arm 25 accommodates the lower 55

portion of the main end-standard A³ when the standard A⁵ is in the open position shown in full lines in Fig. 1. The arm 25 preferably is formed from a heavy steel strip which is bent to desired form. The weight 26 preferably is in the form of a casting having heavy furcations 26^a and having a stem 26^b which is secured to the lower end of the arm 25. The slot or space between the furcations 26^a accommodates the centrally disposed adjusting means for the bearing 3. That is, the slotted weight 26 straddles the bracket 12 and the adjusting shaft 11 when the standard A⁵ is in the full line position shown in Fig. 1.

15 It will be noted that, viewed as shown in Fig. 1, the counterweight provides a movement which tends to swing the standard A⁵ upwardly from the full line position shown in Fig. 1. On the other hand, when the standard A⁵ is in the normal operative position shown by dotted lines in Fig. 1, the weight 26 is substantially within the plane of the pivot 1, so that the standard A⁵ is approximately balanced in the upright position.

20 By the arrangement shown, the swinging standard A⁵ is effectively counterbalanced, and, notwithstanding its heavy weight, may be moved with ease from the operative position to the in-operative position, and vice versa. The standard is shown equipped with a handle 29 by means of which the swinging movements may be effected.

25

30

35 While corrugated bending rolls are shown in the drawings, plain rolls may be employed. Also, the grouping of the bending rolls may be as desired. It is known, for example, to locate the two lower rolls in a horizontal plane and locate the upper roll above the space between the two lower rolls.

The foregoing detailed description has been given for clearness of understanding only, and no unnecessary limitations should be understood therefrom, but the appended claims should be construed as broadly as permissible in view of the prior art.

45 What I regard as new and desire to secure by Letters Patent is:

1. In combination with a machine comprising a set of bending rolls and a frame which comprises a main end-standard equipped with bearings for certain of said rolls and which com-

prises also a pivoted standard adapted to swing downwardly and away from the plane of said main end-standard, said swinging standard having a bearing for one of the rolls: a counter-weight carried by and depending from said pivoted standard adapted to swing beneath said main end-standard and furnish a counterbalancing moment for said pivoted standard. 5

2. In combination with a machine comprising a set of bending rolls and a frame which comprises a main end-standard equipped with bearings for certain of said rolls and equipped below said bearings with a transverse pivot and a swinging standard supported on said pivot having near its upper end a bearing for one of said rolls: a counterweight comprising a bent arm carried by and depending from said second-mentioned standard and adapted to extend beneath said main end-standard when the pivoted standard is in open position, and a weight carried by the lower extremity of said arm located substantially in a vertical line below said pivot when said pivoted standard is in the operative position and housed within the frame when the pivoted standard is in open position. 20 25

3. In combination: a machine comprising a set of bending rolls, a frame which comprises a main end-standard equipped with adjustable bearings for certain of said rolls, an outwardly and downwardly swinging pivoted standard provided with a bearing for one of the rolls, and mediate disposed adjusting means connected with said main end-standard for adjusting said first-mentioned bearings: a counterweight carried by and depending from said pivoted standard, said counterweight being of angular form and extending beneath said main end-standard when the pivoted standard is in open position, said counterweight being formed to clear said adjusting means. 30 35

4. A structure as specified in claim 2, in which said weight is disposed below and substantially in the plane of said pivot when the pivoted standard is in operative position.

5. A structure as specified in claim 3, in which 45
said counterweight is disposed below and sub-
stantially in the plane of said pivot when the
pivoted standard is in operative position.
